UNITED STATES PATENT OFFICE.

HERBERT R. BLISS, OF NIAGARA FALLS, NEW YORK

SHIPPING CASE.

Application filed March 7, 1922. Serial No. 541,673.

To all whom it may concern:

Be it known that I, HERBERT R. BLISS, a citizen of the United States, residing at Niagara Falls, in the county of Niagara and State of New York, have invented certain new and useful Improvements in Shipping Cases, of which the following is a specification.

This invention relates to shipping cases and especially fiber shipping cases. It is the object of the invention to afford a shipping case which will effect a very large saving in material over the common so-called "slotted" container and has full capacity for its dimensions as distinguished from the so-called "recessed end" container. The so-called slotted container is one made from a single blank in which the bottom and top of the case is each formed by two pairs of relatively large overlapping flaps. This container has been very satisfactory in the past but it requires a far greater amount of material than the container about to be described. Where some of the large industries ship thousands of these containers a day a small saving in material amounts to thousands of dollars in the course of a year. Hence it is the aim of all large shippers to adopt for their shipping departments shipping cases which use a minimum amount of material, which afford the maximum strength, and which require as little labor cost in their preparation as possible.

The container about to be described fulfills all these aims and has other advantages which will appear when a detailed description has been given.

In the drawings,—

Fig. 1 is a perspective of the container after being sealed.

Fig. 2 is a perspective of the container before it has been sealed.

Fig. 3 is a plan view of the three blanks showing, diagrammatically, how same are arranged to go together.

Fig. 4 is a plan view showing how the case is sealed.

Figs. 5, 6, 7 and 8 are sections on the lines 5—5, 6—6, 7—7 and 8—8, respectively, of Fig. 4.

Figs. 9, 10 and 11 are perspectives showing the blanks in the three stages of being stitched together.

Fig. 12 is a section on the line 12—12 of Fig. 9.

Fig. 13 is a cross section through one end of the finished case.

In a prior patent, No. 1,414,067, April 25, 1922, a case of this general character is described, but such prior patent claims only the double or bellows-like sealing flap. This double or bellows sealing flap construction may or may not be used with the shipping case constructed of the blank here used and put together in the way here described. In a prior patent 1,452,588, April 24, 1923, the method of sealing a shipping case which is described and shown in this application is described and claimed. However, this method of sealing can be used on the slotted container or a different form of container and hence is a separate invention. In Patent No. 1,430,151, reissued as Patent No. 15,775, the preferred method of constructing the box described and claimed in this application is set forth and claimed. However, the box here described and claimed can be constructed by other methods than that claimed in such patent but not nearly as advantageously. In Patent No. 1,430,150, Sept. 26, 1922, a machine for stitching a container along the lines of said method is described and claimed.

Referring to Fig. 3, it will be seen that three blanks are used, one a main body blank which has the bottom wall *a*, side walls *b* and *c*, and the sealing flaps *e* and *d*. This blank is a rectangular blank with scorings or weakened lines along which it folds. The end blanks are rectangular blanks with shallow corner flaps *w* formed thereon by cutting out the corners and providing scorings. These end blanks are designated *f* and *g*. The corner flaps *w* are very shallow; in fact, they only have to be the width of material necessary to hold a wire stitch.

Now referring to Fig. 9, it will be seen that the main blank can be set over a pair of anvils *h* and *i*. The end blanks can be lapped over the sides of the anvils with one corner flap of each end blank turned over the side wall *c*. Simultaneously a line of stitches can be taken through each corner flap in accordance with the method described and claimed in reissue Patent, No. 15,775, and by a machine such as described and claimed in Patent No. 1,430,150. When this stitching is completed the main blank may be pulled out over the anvil, as shown in the drawings, Fig. 10, and the same

operation taken to unite the corner flaps to the bottom wall of the case, and finally, the main blank may be pulled out another step, as shown in Fig. 11, and the corner flaps of the end blanks stitched to the final side wall *b*. It will be noticed that the stitches in each side and bottom wall are not taken in sequence, as for instance, with the final side wall *b*. The stitch 13 is first taken at one end and then the stitch 14 at the opposite end, whereupon the stitches then follow in sequence. This is not absolutely essential but it is an advantageous operation in connection with the machine described and claimed in Patent No. 1,430,150.

When the case has been thus constructed it may be packed and sealed in accordance with the method described and claimed in Patent No. 1,452,588, to-wit, a blade anvil *j* is first inserted between the large sealing flaps *e* and *d* and under the end blank sealing flap *k*, as shown in Fig. 6. The stitches 1, 2, 3 and 4 are then taken, leaving an unstitched portion at the middle through which the anvil may be inserted to take stitches 5, 6, 7, 8, 9 and 10 along the line of the meeting edges of the large sealing flaps *e* and *d*. Then the anvil may be swung around to take the stitches 11, 12, 13 and 14 to stitch the two large sealing flaps *e* and *d* to the end blank sealing flap *m*. The anvil may then be withdrawn and the stitch 15 taken between the two large sealing flaps *e* and *d* as shown in Fig. 7. This leaves a slightly open space where the final stitch is taken because the sealing flaps are not united to the underlying end blank flap *k*. By using the bellows-like flap described and claimed in Patent No. 1,414,067, this objection is overcome. At the same time, in some places the present construction is preferable to the bellows-like flap.

The great advantage of this type of container over a slotted container is that it eliminates one pair of deep flaps used on both the top and bottom of the slotted container. These deep flaps are always used on a slotted container for they are considered necessary for the silicate form of sealing, and even were my wire stitching form of sealing used, it would be no advantage to lessen their depth because this would only be waste. These end flaps all have to be of the same depth in order to cut out a uniform rectangular blank. Any variation of their depth results in simply wasting material.

The so-called recessed end case has a blank construction somewhat similar to mine but this case does not clinch the stitches on the inside of the container; in fact, the recessed ends are used for the very purpose of clinching the stitches on the outside of the container to permit sealing of the container.

With the recessed end box the full capacity

of the box in accordance with its dimensions is not achieved. Consequently the box is not as economical as mine either in the amount of material required or in the room required for transportation and storage. Furthermore, the recessed end box very often breaks along the projecting edges, it collects water when left out in the weather, and is open to other objections.

The slotted container, of course, avoids most of these disadvantages of the recessed end container. My container eliminates the wide pair of flaps required at the top of the slotted container and entirely eliminates the two sets of wide flaps at the bottom of the slotted container, substituting in place a single, solid wall. This, of course, effects a very large saving in material, which runs into a great deal in the course of a year. Furthermore, my container has a reinforcement stitched around all corners of the box, which makes it very much stronger than either the slotted container or the recessed end container. It is stronger than the slotted container because the slotted container does not have a double wall at the corners. The recessed end case does have a double wall at the corners but this wall is a projecting and an exposed one and it makes it easy to tear.

By the use of a machine such as shown in my Patent No. 1,430,150, which simultaneously stitches both ends of the blank, practically no more labor or effort is required in stitching the box and setting it up than is the case with the slotted container.

It will be obvious that the corner flaps can be stitched to the inside of the side walls and bottom walls in place of the outside without altering the principle of the invention, so the statements in the claims must be interpreted with either way of stitching the end blank flanges to the main body blank walls in view.

One of the features of this form of box and blank is that it can be readily made up with vertical grain board, which is not practical with a slotted container altho theoretically possible. Vertical grain board is very much stronger.

It will also be obvious that the position of the corner flaps as to the blanks and the location of the narrow and broad sealing flaps in the several blanks might be shifted without departing from my invention, hence the claims have been accordingly formulated to cover such changes.

What I claim is:

1. A shipping case of foldable board, comprising three separate blanks some of which are provided with integral foldable corner flaps, two of the blanks being end blanks forming each an end of the case, the remaining blank forming the bottom and two side walls, the end blanks being set in substan-

tially flush with the ends of the main blank and held there by the corner flaps being folded and secured to the adjoining blank, the three said blanks being provided at top 5 or charging side of the case with an aggregate of three or more sealing flaps each integral with a blank, all folded in, and some overlapped and the adjacent flaps stitched together without the material of the case 10 being slotted to effect such stitching.

2. The combination stated in claim 1 in which there are four sealing flaps with two being relatively narrow and stitched to the other two flaps along the length of the narrow flaps.

3. The combination stated in claim 1 in which the corner flaps are integral with the end blanks and stitched to the body blank.

4. The combination stated in claim 1 including 20 four sealing flaps two of which are relatively narrow and integral with the end blanks.

5. A shipping case constructed of fibre board or equivalent material, comprising 25 three separate substantially rectangular blanks cut and creased to provide two independent end blanks and one independent body blank, some of the blanks provided with integral shallow corner flaps that are foldable to lie against the adjoining blank 30 with the ends of the case substantially flush with the ends of the body blank when the

latter is folded up to form the bottom and two side walls of the case, the corners thus formed being substantially clear and unobstructed inside and out, the said three separate blanks arranged to present at the top of the case where it is charged a set of three or more sealing flaps each integral with a blank, all of which fold in and some of 40 which overlap and two of which are relatively narrow, means for fastening the corner flaps to the blank or blanks against which they lie, and means for fastening the narrow sealing flaps to the remaining sealing flap 45 or flaps, said last mentioned means consisting of fasteners driven in and clinched, without the material of the case being slotted to effect such clinching.

6. The combination stated in claim 5 with 50 the narrow sealing flaps integral with the end blanks.

7. The combination stated in claim 5 with the shallow corner flaps integral with the 55 end blanks.

8. The combination stated in claim 5 with both the shallow corner flaps and narrow sealing flaps integral with the end blanks.

9. The combination stated in claim 5 with 60 two relatively narrow sealing flaps and two remaining sealing flaps all wire stitched together.

In testimony whereof I affix my signature.
HERBERT R. BLISS.
